Primary Examiner — Ricky Pham(74) *Attorney, Agent, or Firm* — Birch, Stewart, Kolasch & Birch, LLP(57) **CLAIM**

We claim the ornamental design for a coffee roaster for toaster oven, as shown and described.

DESCRIPTION

FIG. 1 is a perspective view of a coffee roaster for toaster oven showing a new design;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing a state of use thereof. The broken lines in FIG. 8 are for environment purpose only and form no part of the claimed design.
